BUTTON ZITHER

Clair Omar Musser, 12997 Blairwood Drive,
Studio City, Calif. 91604

Filed July 6, 1965, Ser. No. 86,038

Term of patent 14 years

(Cl. D56—1)

FIG. 4.

FIG. 5.

FIG. 6.

FIG. 1 is a right end, top and rear perspective view of a button zither, showing my new design;

FIG. 2 is a front elevational view, to a larger scale;

FIG. 3 is a right end elevational view, to the same scale as FIG. 2;

FIG. 4 is a top plan view, to the same scale as FIG. 2;

FIG. 5 is a rear elevational view to the same scale as FIG. 2; and

FIG. 6 is a left end elevational view thereof to the same scale as FIG. 2.

The bottom thereof is plain.

I claim:

The ornamental design for a button zither, substantially as shown and described.
